UNITED STATES PATENT OFFICE

158,347

TEXTILE FABRIC

Phyllis Wayne, Los Angeles, Calif., assignor to
Harry Goldinger Textile Corporation, Los Angeles, Calif., a corporation of California

Application September 27, 1948, Serial No. 148,790

Term of patent 14 years

(Cl. D92—1)

To all whom it may concern:

Be it known that I, Phyllis Wayne, a citizen of the United States of America and residing at Los Angeles, in the county of Los Angeles and State of California, have invented a new, original, and ornamental Design for a Textile Fabric of which the following is a specification, reference being had to the accompanying drawing, forming a part thereof.

The figure is a plan view of a piece of textile fabric showing my new design. The design unit is outlined by dotted lines, which unit is repeated over the textile fabric as indicated by the extensions beyond the unit boundaries.

I claim:

The ornamental design for a textile fabric, as shown and described.

PHYLLIS WAYNE.
